THERMOMETER

Edward J. Plavcan, Stratford, Conn., assignor, by mesne assignments, to Dresser Industries, Inc., Dallas, Tex., a corporation of Delaware

Filed Jan. 7, 1963, Ser. No. 73,066

Term of patent 14 years

(Cl. D52—7)

FIG. 1 is a side elevational view of a thermometer embodying my new design.

FIG. 2 is a bottom view of the thermometer of FIG. 1.

FIG. 3 is a top view of the thermometer of FIG. 1.

The essential features of the design reside in the full line portions.

I claim:

The ornamental design for a thermometer, as shown and described.
